UNITED STATES PATENT OFFICE.

ISAAC HOLZMARK, OF KANSAS CITY, MISSOURI.

DESIGN FOR A CARPET-MOLDING.

SPECIFICATION forming part of Design No. 15,832, dated February 17, 1885.

Application filed October 4, 1884. Term of patent 7 years.

To all whom it may concern:

Be it known that I, ISAAC HOLZMARK, of Kansas City, Jackson county, Missouri, have invented and produced a new and original Design for Ornamental Carpet-Moldings, of which the following is a full, clear, and exact description, reference being had to the accompanying drawings, in which similar letters of reference indicate corresponding parts.

10 Figure 1 is a plan of my newly-designed molding. Fig. 2 is a plan view showing the general outlines of the said molding.

Heretofore fastenings for carpets that were in the form of moldings or strips have been 15 constructed, usually, without regard to ornamental outlines—that is, the edges of the strips were undisturbed straight lines.

The principal feature of my design consists of the ornamental wings A, projecting from 20 one side of the body of the molding K and ter-

minating with the pointed extremity a. The circular spaces P separate the said projecting wings from each other. The triangular apertures B, which are upon a direct line with the edges of the strip and at a uniform distance 25 therefrom, form a part of the wings A, and impart to them a comparatively artistic and finished form, as shown.

I claim—

The design for a carpet-molding herein 30 shown and described, the same consisting of the ornamental wings A, projecting from the body of the molding K.

In testimony whereof I affix my signature in presence of two witnesses.

ISAAC HOLZMARK.

Witnesses:

HENRY D. ASHLEY,
HERMAN HOLZMARK.
